(57) **CLAIM**

The ornamental design for a contoured interdental space cleaner, as shown and described.

DESCRIPTION

FIG. 1 is a top perspective view of a contoured interdental space cleaner showing my new design;

FIG. 2 is a top plan view thereof shown on a slightly reduced scale;

FIG. 3 is a left side elevation thereof;

FIG. 4 is a right side elevation thereof or elevation thereof;

FIG. 5 is a front elevation thereof; and,

FIG. 6 is a rear elevation thereof.

The broken lines shown in the drawings are included for the purpose of illustrating environmental structure and form no part of the claimed design.
